UNITED STATES PATENT OFFICE

98,600

DESIGN FOR A LUMINOUS-ARM SIGNAL

Donald A. Lee, Oakland, Calif.

Application January 23, 1935, Serial No. 55,007

Term of patent 14 years

To all whom it may concern:

Be it known that I, Donald A. Lee, a citizen of the United States, and a resident of Oakland, in the county of Alameda and State of California, have invented a new, original, and ornamental Design for Luminous-Arm Signal, of which the following is a specification, reference being had to the accompanying drawing, forming part thereof, wherein,

Figure 1 is a front elevation of the signal.

Figure 2 is a side elevation of the signal.

Figure 3 is a fragmentary front view of a top portion of the signal with a front lens thereof removed.

Figure 4 is a sectional view at 4—4 in Figure 1.

I claim:—

The ornamental design for a luminous-arm signal, substantially as shown.

DONALD A. LEE.
